RADIO ALARM TRANSMITTING, RECORDING, AND SIGNALING SYSTEM

Paul E. Fischler, Buffalo, N. Y., assignor of one-half to John Nathanson, Buffalo, N. Y.

Application March 3, 1949, Serial No. 79,323

11 Claims. (Cl. 177—354)

1

This invention relates to a radio alarm transmitting, recording, and signalling system and may be used wherever such systems are necessary or desirable.

It is particularly well adapted for use as a fire alarm system, and by way of illustration, it will be described in connection with such systems, although its use is not limited thereto.

In rural or suburban areas the fire alarm systems are generally inadequate or non-existent because of the poles and wires necessary with an adequate number of pull boxes, and the cost of known systems is usually beyond the means of small communities and the maintenance of wired systems is comparatively high because of the exposed wire plant.

Most communities are dependent upon the telephone to notify the fire house in time of fire and the time lost between the discovery of a fire and the notification of the fire company and the assembling of men and apparatus at the scene of the fire is often considerable.

The system herein described has for its object the solution of the foregoing and other problems commonly met with in connection with fire alarm systems, as by the use of the present system, the signals are transmitted from the pull boxes to the fire house in which the receiver is located without the use of wires and the pull boxes, when operated, automatically transmit impulses and put into operation a fire alarm which will be broadcast by a siren at the fire house or wherever the receiver is located, said broadcast to be followed by a coded air horn signal by which all those within hearing can determine which pull box is operated. These signals may be repeated any number of times.

An object of the invention is to provide a transmitter pull-box having a spring motor controlled by a manually operable lever, which when released, will cause the device to automatically release a series of signal pulses automatically repeated any desired number of times. This eliminates such difficulties as occur from the use of telephone dial switches or the like, which must be correctly manipulated by the user or a wrong signal will result.

Another object of the invention is to provide a transmitter pull-box which is automatically resetting after use.

Another object is to provide an audio impulse recording device in which all stepper relays and selector switches are eliminated and in which the incoming signals from the pull-boxes are recorded on a tape, which in turn operates signalling devices such as a siren and air horn.

2

A further object is to provide a signalling device in which incoming signals from any number of pull boxes may be "stored" on the tape at one minute intervals, the signalling mechanism being automatically maintained in operation until all "stored" signals have been coded by the air horn.

In the accompanying drawings:

Figure 1 is a diagram of the audio impulse coding mechanism for use at a pull-box used with the alarm system embodying the invention;

Figure 2 is a sectional view on the line 2, 2 of Figure 1;

Figure 3 is a side view of the door 15 of the cast aluminum housing 62 (Figure 5) showing the actuating lever 14 supported thereon.

Figure 4 is a diagram of the audio impulse recording and signalling device operated by the pull boxes shown in the preceding figures; and

Figure 5 is a diagram of the apparatus shown in the preceding figures connected to form the complete radio alarm transmitting, recording and signalling system herein described.

25 *Audio impulse coding mechanism for radio alarm pull-box*

This mechanism, driven by a spring motor, is used to control the operation of a radio transmitter, modulated with a selected audible tone in the frequency spectrum between 100 and 8,000 C. P. S. modulation occurring as a series of pulses so spaced as to indicate the number of the pull-box.

The National Board of Fire Underwriters requirements state that no box number shall be composed of more than three digits, and that these digits must be repeated four times when sounding an alarm. The coding mechanism to be described was designed, therefore, to code any box number from 2 to 999, and to repeat the digits four times. Numbers 1, 10, 11, 20, 30, etc. are omitted as they cannot be clearly coded.

For accuracy of transmission, the pulse speed is set at three per second, with intervals of one second between digits and two seconds between groups of digits. Since 999 is the highest number to be coded, 50 seconds are required to transmit this number four times.

A mounting plate 10 carries the spring motor 10a which is connected to shaft 11 through gear 11a to drive discs 12 and 13 at 1 R. P. M. When the actuating lever 14 mounted on door 15 is depressed, the cam 16 on said lever engages the hinged latch bar 17 at point 18, closing the contacts 19, 20 to energize the transmitter tube filaments hereinafter referred to.

This action also raises the opposite end of the latch bar out of slot 21 in disc 12, allowing discs 12 and 13 to rotate. The latch bar 17 rides on the face of the disc 12 during rotation, thereby maintaining contacts 19, 20 closed. The actuating lever 14 returns to its normal position by reason of the pressure of spring 22.

The transmitted tube filaments are allowed to reach normal operating temperature during the first 10 seconds of disc rotation by reason of the cut-away portion 23 on disc 13. Coding teeth 24 on the disc 13 are then in position to actuate contacts 25, 26 which close a circuit causing the audio oscillator to modulate the transmitter with pulses designating the pull-box number all as presently described.

Upon completion of one revolution of discs 12, 13, the latch bar 17 under pressure of spring 21 falls back into slot 21 stopping the motor. This action also opens filament contacts 19, 20. The mechanism is now automatically reset for subsequent operation.

In practice, the disc 13 is fabricated with teeth equally spaced around the entire circumference and it is then milled to remove those teeth not required.

Audio impulse recording and signaling device

This device is designed to operate from the output of a suitable receiver as shown in Fig. 5 to record coded audio signals from the pull-boxes shown in Figs. 1 to 3 inclusive, and to employ these recorded signals to automatically operate a warning siren followed by air-horn signals designating the number of pull-box. Reference is now made to Fig. 4.

Standard type paper tape 28 is stored on the reel 29 and threaded through guide wheels 30, 31 over drive disc 32, through guide wheels 33, 34, and over disc 35.

Drive disc 32 has a diameter of 2½ inches and is geared to synchronous motor 36 to rotate in a clockwise direction at a speed of 4 R. P. M. Therefore, 31.4 inches of tape pass over this disc per minute. Since it requires 50 seconds for the highest pull-box number, 999, to be transmitted and received, 26.2 inches of tape will be employed in recording these signals, and the remaining 5.2 inches is required to span the distance between perforating punch 37 and signaling contacts 38 and 39.

Drive disc 35 also has a diameter of 2½ inches and is geared to synchronous motor 40 to rotate in a clockwise direction at a speed of 1½ R. P. M., thereby allowing 31.4 inches of tape to pass over this disc in a 3 minute period. This reduced rate of tape travel allows 30 seconds for siren actuation during travel of the uncoded 5.2 inches of tape from perforating punch 37 to signaling contacts 38 and 39. Also, the following coded tape allows contacts 38 and 39 to close for one second for each recorded pulse, with three seconds space between digits and six seconds space between groups of digits.

Disc 41 has a diameter of 2½" and is geared to disc 32 to rotate in a counterclockwise direction at a speed of 1 R. P. M. Disc 42 has a diameter of 2½ inches and is geared to disc 35 to rotate in a counterclockwise direction one revolution in three minutes.

The reception of the first pulse of a series of pulses of proper audio frequency operates the tuned audio relay 43 to close its contacts 44 and 44a. This completes an A. C. circuit to the perforating coil 45 and relay coil 46. Relay 46 locks

in through contacts 47, 48, 49, 50. Contacts 51 and 52 also close to complete A. C. circuit to motor 36. Contacts 53 and 54 are adjusted to open after contacts 47, 48, 49 and 50 have closed, thereby opening lead to coil 46 from contact 44 of relay 43, preventing shorting of contacts 44 and 44a of relay 43 when relay 46 locks in. Drive disc 32 starts to rotate, causing slack to form in tape 28 shown by loop 55, thereby closing tape-pressure controlled contacts 56, 57 which complete an A. C. circuit to motor 40, starting rotation of drive disc 35. Subsequent pulses continue to operate relay 43 and coil 45 and tape 28 is coded by perforating tool 37. The speed of rotation of disc 32 being greater than that of 35 will cause the tape to loop at 55 as shown.

At the end of a one-minute period, disc 41 will have made one revolution and cam 58 will open contacts 49 and 50 to de-energize relay 46 and open contacts 51 and 52 to stop motor 36. Disc 35 will continue to rotate until tape becomes taut and opens contacts 56 and 57 to stop motor 40.

Cam 59 on disc 42 closes siren control contacts 60 and 61 for first 15 seconds of rotation. This allows the siren to reach maximum speed, and another 15 seconds is required for it to coast to a stop. By this time the perforated portion of the tape has reached air-horn control contacts 38 and 39, which then close and open to audibly sound the pull-box number.

After a one minute period a second alarm may be "stored," the first pulse repeating the operation previously explained and the tape 28 will form a loop 55 as shown. As a precaution against "jamming," instructions may be placed on each pull-box, advising not to actuate the box for one minute after the starting of a siren signal warning of a previously received alarm.

Operation of radio alarm transmitting, recording and signaling system

Having described the construction and operation of the pull-box audio impulse coding mechanism and the audio impulse recording and signaling system, reference is now made to Fig. 5 for the purpose of explaining the operation of the complete radio alarm system.

Transmitting unit

The transmitter, audio impulse coding mechanism generally indicated at 63, vibrator type plate power supply 64 and 6 volt battery 65 are housed in a weather proof aluminum case 62. Power from the transmitter is fed to a half-wave dipole antenna 66 by means of coaxial cable 67.

Access to the actuating lever 14 is had by opening a small auxiliary door on the large door 15 of the housing 62. When this lever is depressed as explained in connection with Figs. 1 to 3 inclusive, its cam action places the impulse coding mechanism in operation. The contacts 19, 20 close to complete a circuit from battery 65 to the tube filaments, and also to the input of plate power supply 64. After a 10 second transmitter warm-up period, the coding teeth on disc 13 of the coding mechanism 63 are in position to close contacts 25, 26, thereby completing the plate circuit of the audio oscillator, allowing it to generate pulses of a selected audio frequency, which are employed to drive the modulator tube. Radio frequency power, modulated with audio pulses designating the pull-box number, is radiated from the antenna 66.

After repeating the pull-box designating signals four times, the coding mechanism stops, auto-

matically opening the battery circuit to filaments and plate power supply, and also resetting the actuating lever for subsequent operation.

Recording and signalling unit

The recording and signalling unit is comprised of a suitable type radio receiver 68 having its output circuit connected as shown to a tuned audio relay 43. This, together with an audio impulse recording and signalling system assembly, is mounted in the ventilated steel cabinet 69. External to the cabinet is the dipole antenna 70 and connecting coaxial cable 71 and a siren 8 and coding air-horn AH.

Coded signals from the transmitting unit are conveyed from the dipole antenna to the receiver, and appear in the output circuit as audio pulses. If the values of L and C of tuned audio relay 43 are chosen to cause circuit resonance at the audio pulse frequency, the contacts 44 and 44a will close for each pulse received. Closing of contacts 44 and 44a completes an energizing circuit to the perforating coil 45 and relay 46. Operation of the recording and signalling unit is then as described in explanation of Fig. 4, causing the siren S to sound for 30 seconds followed by operation of the air-horn connected at AH to code the number of the transmitting pull-box.

While the system as shown employs the transmission and reception of amplitude modulated radio signals, it will operate equally as well with phase or frequency modulated signals.

As the construction of spring-driven motors such as that employed in the pull-box Fig. 1 to drive discs 12 and 13 is well known, same is not described herein in detail. This also applies to the details of construction of the crystal controlled transmitter, plate power supply, crystal controlled receiver and other component parts which are of any suitable construction.

And, while a preferred embodiment of the invention has been described by way of illustration, it will be understood that many changes and modifications can be made therein without however, departing from the appended claims which define the invention herein set forth.

What is claimed is:

1. A radio transmitter comprising a crystal controlled R. F. oscillator, a R. F. amplifier, an audio oscillator, a modulator adapted to modulate the R. F. amplifier with single frequency pulsed audio tones, a power supply, a spring actuated impulse coding mechanism including an actuating lever adapted to be manually moved to release said mechanism, a first contact operated by the movement of said lever for controlling the application of filament voltage to all tubes and plate voltage to the R. F. and modulator tubes of said transmitter, a pulsing member having coding teeth forming part of said mechanism, and a second contact actuated by said teeth for controlling application of plate voltage to the audio oscillator of said transmitter causing the modulation of the R. F. carrier current with a series of audio pulses corresponding to the number and spacing of said coding teeth, said coding mechanism adapted to maintain the pulse transmission at a selected speed.

2. A radio transmitter as claimed in claim 1 wherein said first contact is timed to close a predetermined time prior to the operation of said second contact.

3. A radio transmitter as claimed in claim 1 wherein said pulsing member comprises a disc

having teeth extending radially from its periphery, said teeth being disposed in spaced-apart groups, each group comprising more than three teeth, the speed of the pulses produced by said pulsing member being present at 3 per second, with intervals of one second between digits and two seconds between groups of digits.

4. In a radio transmitter of the type described wherein there are instrumentalities including a transmitting tube necessary to transmit a radio frequency carrier wave modulated with pulsed audio tones of a selected frequency, a motor, a first disc, impulse mechanism including a contact adjacent said disc and adapted to be operated by the rotation thereof, a second disc, a pivoted latch bar associated with said second disc and normally restraining both said discs from rotation, a manually operable actuating lever adapted to engage said latch bar and move the same to release said discs for rotation by said motor and a contact actuated by said lever to control the application of filament voltage to the transmitter tubes.

5. The combination as claimed in claim 4 wherein said second disc has a radial slot into which the free end of said latch projects.

6. In an audio impulse recording and signalling device including a radio receiver having an output circuit, a tuned audio relay connected to said output circuit for actuation by audio pulses delivered thereto via said circuit, contacts controlled by said relay, a perforating mechanism controlled by said contacts, a second relay controlled by said contacts, locking contacts on said second relay to hold same closed upon energization of said relay, first and second motors controlled by said second relay, a tape adapted to be perforated by said perforating mechanism and moved by said first motor, contacts controlled by said tape for controlling said second motor, means controlled by said second motor for producing a first audible signal, and a second audible signal controlled by contacts operated by perforations in said tape.

7. The combination as claimed in claim 6 including means controlled by said first motor for opening the circuit to said motor after a predetermined period.

8. The combination as claimed in claim 6 wherein said means controlled by said second motor for producing said first audible signal includes contacts cyclically controlled by said second motor to energize said signal during a predetermined operation of said second motor.

9. The combination as claimed in claim 6 including members driven by said motors for moving said tape, said motors operating at such speeds that a loop of said tape is formed therebetween during a predetermined period of operation of said motors.

10. In a system of the class described, a manually operable pulse generator including a spring-operated contact device adapted to control the transmission of audio tone modulated radio signals in a series of repetitive groups of impulses, a radio receiver adapted to receive such signals and produce corresponding groups of audio pulses, a tuned audio relay operable by said audio pulses, means controlled by said relay for moving and perforating a tape, means controlled by said tape for terminating the movement thereof, and means controlled by said tape for broadcasting audible signals corresponding to said audio pulses.

11. In a system of the class described, wherein there is a radio transmitter, instrumentalities necessary to modulate the radio frequency carrier of said transmitter with repetitive groups of single frequency audio tones, a motor, a first disc, pulsing mechanism including contacts adjacent said disc and adapted to be operated by the rotation thereof, a second disc, a pivoted latch-bar associated with said second disc and normally restraining both said discs from rotation, a manually operable actuating lever adapted to engage said latch-bar and move the same to release said discs for rotation by said motor, and contacts actuated by said lever and said second disc to control the application of filament voltage to the tubes of said radio transmitter.

PAUL E. FISCHLER.
